UNITED STATES PATENT OFFICE.

JOSEPH A. WIEDEMANN, OF ELDORADO, KANSAS.

SIGN.

No. 831,397.

Specification of Letters Patent.

Patented Sept. 18, 1906.

Application filed April 5, 1906. Serial No. 310,101.

To all whom it may concern:

Be it known that I, JOSEPH A. WIEDEMANN, a citizen of the United States, residing at Eldorado, in the county of Butler and State of Kansas, have invented certain new and useful Improvements in Signs; and I do declare the following to be a full, clear, and exact description of the invention, such as will enable others skilled in the art to which it appertains to make and use the same.

My invention relates to improvements in signs for use in stores and store-windows for advertising purposes; and it consists of the novel features of construction, combination, and arrangement of parts hereinafter described and claimed.

One object of the invention is to provide a simple and inexpensive sign of this character in which the letters, figures, and other reading matter will be given an attractive shimmering appearance to draw the attention of passers-by to the sign.

Another object of the invention is to provide a device of this character which may be illuminated, so that it may be used at night for display purposes in store-windows.

A further object of the invention is to improve and simplify the construction and operation of devices of this character, and thereby render the same more efficient and less expensive.

The above and other objects which will appear as the nature of my invention is better understood are accomplished by means of the construction illustrated in the accompanying drawings, in which—

Figure 1 is a perspective view of my improved sign. Fig. 2 is a vertical front to rear sectional view through the same. Fig. 3 is a rear elevation of the sign with parts broken away and showing its combined rear door and clamping-support in its closed position. Fig. 4 is a front view of the rotary screen-carrying wheel. Fig. 5 is a view of one of the colored screens or disks. Fig. 6 is a perspective view of one of the blades or buckets for the screen or disk-carrying wheel, and Figs. 7 and 8 are detail views of slightly-modified forms of the invention.

Referring to the drawings by numeral, 1 denotes the housing or casing of my improved sign, which casing, as here shown, is in the form of a rectangular box having its front closed by a hinged door 2, which bears the sign proper, 3. The latter may be of any form and construction; but I preferably make

it of opaque material and have the letters, figures, or other reading matter for the sign transparent. This sign 3 is removably mounted, as shown, so that it may be changed for a similar one bearing different reading matter. The closed rear wall of the casing 1 is formed with a centrally-disposed opening closed by a small door 4, which is hinged to swing downwardly to a horizontal position and form a shelf for a lamp or other suitable illuminating device 5, which is adapted to illuminate the sign 3, so that rays of light will pass through its transparent reading matter. This door 4 may be held closed by a suitable turn-button, as shown in Fig. 3, and it is supported in its open horizontal position by a triangularly-shaped bracket 6, which is hinged upon its outer face and foldable against the same when the door is closed. The lamp 5 is preferably mounted in a rectangular box or casing 7, which has its open face disposed opposite the opening in the rear wall of the casing and its perforated bottom supported by short legs above the door or shelf 4 when the latter is in its lowered horizontal position. (Shown in Fig. 2 of the drawings.)

In order to give the reading matter of the sign an attractive shimmering appearance, I rotate within the casing a screen or disk 8, having differently-colored portions or sections. If desired, this disk may be made of cardboard and have only its front face colored; but when the lamp or illuminating device 5 is employed this screen or disk is made transparent and has differently-colored portions, so that the colors of the rays of light shed through the transparent portions of the same will be constantly changed. This screen or disk 8 is removably retained by means of clips or the like 9 in an annular seat 10, formed in the rim 11 of a wheel 12. The latter has the web portion 13 of its rim 11 connected by spokes 14 to its hub 15, which is mounted by means of ball-bearings upon a shaft 17, provided in suitable supports or bearings 18. This screen or disk-carrying wheel 12 may be rotated in any suitable manner, but I preferably employ a lamp 19, which has its chimney projecting through an opening 20 in the bottom of the casing adjacent to one end, so that the heat of said lamp will be directed into pockets or buckets 21, secured upon the rear or inner face of the web portion 13 of the rim of the wheel. These pockets or buckets are arranged in an annular row and

are preferably formed by bending pieces of metal into V form and bending their ends to provide attaching-flanges 22, which are riveted, soldered, or otherwise secured to the 5 rim, as clearly shown in the drawings. In the top of the casing 1, at the corner diagonally opposite that in which the opening 20 is located, is formed an outlet-opening 23, through which the heat and products of combustion escape after acting upon and rotating the wheel 12. If desired, the lamp 19 may have its chimney projecting through a centrally-disposed opening in the bottom of the casing, so that its heat will be directed 10 against the pockets or buckets upon a pair of wheels 12^a, as shown in Fig. 7 of the drawings, so that two of such wheels may be operated by the one lamp, and, if desired, four of such wheels may be operated by the one 15 lamp, as shown in Fig. 8 of the drawings; this being done by the provision of a Y-shaped conductor, as will be readily understood upon reference to Fig. 8.

From the foregoing description, taken in 20 connection with the accompanying drawings, the construction and operation of the invention will be readily understood without requiring a more extended explanation.

Various changes in the form, proportion, 25 and the minor details of construction may be resorted to without departing from the principle or sacrificing any of the advantages of this invention as defined by the appended claims.

Having thus described my invention, what I claim as new, and desire to secure by Letters Patent, is—

1. A sign comprising a casing having transparent reading matter in one of its walls, a 30 rotary screen-carrying wheel within said casing in rear of said reading matter, an annular row of pockets or buckets upon said wheel, and a lamp mounted to direct the heated air from its chimney into said pockets or buckets.

2. A sign comprising a casing having transparent reading matter in one of its walls, a 35 rotary screen-carrying wheel within said casing in rear of said reading matter, an annular row of pockets or buckets upon said wheel, a lamp mounted to direct the heated air from its chimney into said pockets or buckets, and means for supporting an illu-

minating device in rear of the screen upon said wheel.

3. A sign comprising a casing having transparent reading matter in one of its walls, a 40 wheel mounted to rotate in said casing, a screen removably mounted upon the front face of said wheel, an annular row of pockets or buckets upon the rear face of said wheel, a lamp mounted to direct the heat from its chimney into said pockets or buckets, and means for supporting an illuminating device in rear of said wheel and the screen thereon.

4. A sign comprising a casing having transparent reading matter in one of its walls, a 45 wheel mounted to rotate in said casing and having an annular seat in its front face, a screen or disk engaged with said seat, clips for removably retaining said screen therein, an annular row of pockets or buckets extending 50 from the rear face of said wheel, and means for directing a blast of air into said pockets or buckets.

5. A sign comprising a casing having a door 55 at its front and openings in its top and bottom at diagonal opposite corners, a removable sign proper upon said door having transparent reading matter, a wheel mounted to rotate in said casing and having an annular 60 seat in its front face, a transparent screen or disk engaged with said seat, clips for retaining the same in said seat, V-shaped metal pockets or buckets having attaching-flanges secured upon the inner face of said wheel, a lamp having its chimney projecting into the 65 opening in the bottom of said casing to direct its heat into the pockets or buckets on said wheel, a hinged door closing a central opening in the rear of said casing, and a folding 70 bracket upon said door to support the latter in a horizontal position, a second lamp, and a removable housing for the latter adapted to be mounted upon said door when the latter is supported in a horizontal position by said 75 bracket.

In testimony whereof I have hereunto set my hand in presence of two subscribing witnesses.

JOSEPH A. WIEDEMANN.
